UNITED STATES PATENT OFFICE.

LOUIS FRANCIS CLARK, OF GRAND RAPIDS, MICHIGAN, ASSIGNOR OF ONE-HALF TO
IRVING A. ANDERSON, OF GRAND RAPIDS, MICHIGAN.

INTERNAL-COMBUSTION ENGINE.

1,106,365.

Specification of Letters Patent. Patented Aug. 11, 1914.

Application filed November 20, 1911, Serial No. 661,369. Renewed January 2, 1914. Serial No. 810,051.

To all whom it may concern:

Be it known that I, LOUIS FRANCIS CLARK, a citizen of the United States of America, residing at Grand Rapids, in the county of 5 Kent and State of Michigan, have invented certain new and useful Improvements in Internal-Combustion Engines; and I do hereby declare the following to be a full, clear, and exact description of the invention, such 10 as will enable others skilled in the art to which it appertains to make and use the same.

My invention relates to improvements in internal combustion engines and more particularly to that type commonly known as 15 the four cycle engine and its object is to do away with the ordinary puppet valves and mechanism connected therewith used in this type of engine and to provide an engine simple in construction, positive in operation and practically noiseless. Heretofore it has been the custom in nearly all types of the four cycle engine to use puppet valves to admit the combustible charges and let out 20 the burned charges from the cylinders. In order to operate these valves it was necessary to provide in most cases a cam shaft driven by gears from the crank shaft of the engine, push rods or like devices to operate 25 the valves from the cam shaft and springs to hold the valves normally closed. This valve operating mechanism is objectionable because of the various parts employed, the liability of these parts to become worn and 30 get out of adjustment and the noise made by this mechanism when in operation. In my newly invented engine I do away altogether with the puppet valves and their operating mechanism by using a device hereafter more 35 fully described and particularly pointed out in the claims reference being had to the accompanying drawings, in which:

Figure 1 is a vertical section of an engine 40 embodying my invention, this section being taken through the axis of the crank shaft; Fig. 2 is a rear elevation of the engine showing the inlet and outlet pipes and carburetors; Figs. 3, 4 and 5 are sectional details 45 of a portion of the cylinder with the piston showing three different stages of the operation of the engine, these figures are viewed from the direction of the inlet and outlet ports; Figs. 6, 7 and 8 are respectively horizontal sections on the lines 6—6, 7—7 and 50 8—8 of Figs. 3, 4 and 5; Fig. 9 is a rear view

of a part of the cylinder with the inlet and outlet pipes removed showing the inlet and outlet ports in the cylinder; Fig. 10 is a plain view of the piston head; Fig. 11 is an inverted sectional plan of the piston taken on 55 the line 11—11 of Fig. 1; Fig. 12 is a transverse sectional detail of a portion of the piston showing the compression bar section; Fig. 13 is an enlarged plan of a portion of the rotating ring which carries the upright 60 bar to rotate the piston; and Fig. 14 is a vertical sectional detail showing a portion of the said ring and bar together with the gear attached to the ring.

Like numbers refer to like parts in all of 70 the figures.

1 represents the crank case provided with bearings in which the crank shaft 2 is journaled; 3 the fly wheel; 4 the cylinder; 5 the piston; 6 the connecting rod which is attached in the usual way to the crank at its lower end and connected to the piston at its upper end to both swing in the piston and to permit the piston to rotate thereon, preferably by a ball and socket joint 7. A half 75 time shaft 8 is journaled in a bushing in the crank case and is located above and parallel with the crank shaft. This half time shaft 8 is provided with a gear 9 which meshes with the gear 10 fixed on the crank shaft. 80 These gears are of such proportion that the shaft 8 will be driven at half the speed of the crank shaft. A bevel gear 9^a is also fixed on the half time shaft and meshes with and drives the bevel gear 11 which rotates 85 at right angles to the crank shaft. The gear 11 is attached to a ring 12 rotatably mounted at the base of the cylinder, and an upwardly extending bar 13 is mounted on the ring 12 and rotates therewith. The upper 90 end of this bar 13 projects into the piston and is vertically slidable in a plate 14 attached in the lower part of the piston. As the gear 11 and ring 12 rotate they will also rotate the piston by means of the bar 13, the 95 piston being free to reciprocate vertically on said bar.

In order to admit the combustible mixture to the cylinder and exhaust the burned charges therefrom, an inlet port 15 and exhaust port 16 are provided in the lower part 100 of the cylinder and are covered at all times by the piston. The piston is provided with a passage 17 segmental in horizontal section and open at its top through the piston head. 110

This passage is provided with lateral ports 18, 19 and 20 through the side of the piston which are so arranged that at the proper time in the operation of the engine they will 5 communicate with the ports 15 and 16 in the cylinder wall to admit the charge or to exhaust it from the cylinder through the chamber 17. In order to prevent the incoming or outgoing charge from escaping 10 through the wrong port by following whatever space there may be between the piston and cylinder wall compression bars 21 arranged longitudinally of the piston are let into the side of the piston and held in contact 15 with the cylinder wall by springs 22.

The operation of this engine is as follows. Assuming the piston to be at the end of its working stroke and about to begin the exhaust or scavenging stroke as shown in Fig. 20 3. At this point the port 20 in the piston is partially opposite the exhaust port 16 in the cylinder wall. As the piston rises on its exhaust or scavenging stroke it will also rotate within the cylinder and the ports in its 25 side will follow a helical path exposing first the port 20 and then the port 19 to the exhaust port 16 and allowing the burned gas within the cylinder to escape through the passage 17 and the exhaust outlet. The position 30 of the piston at the end of this stroke is illustrated in Fig. 4. The piston now is about to begin its inspiration stroke. In doing this it travels downward and rotates at the same time exposing the ports 19 and 35 18 to the inlet port 15 in the cylinder wall thus allowing the suction produced in the cylinder to draw in a fresh charge through the carbureter. The piston is shown at the completion of this stroke in Fig. 5. To complete 40 the cycle of operations the piston must now travel upward on its compression stroke and downward again on its working stroke in order to again attain the position shown in Fig. 3. During these two strokes the ports 18, 45 19 and 20 are opposite the solid cylinder wall consequently, no gas can escape through them. The half time shaft 8 also serves as a shaft for the usual commutator or timer 23.

In the foregoing description, I have not 50 attempted to describe any specific ignition system, as any form of ignition commonly used at the present time may be used on this engine and any other accessory parts will also be any of the ordinary types. 55 It will be clearly seen that this engine is simple and comparatively cheap to construct there being no valves to be accurately seated and timed, the inlet and outlet passages to and from the cylinder being accurately and 60 positively timed by the means heretofore described. This mechanism is also practically noiseless in operation as such moving parts which usually tend to produce noise may be conveniently inclosed within the 65 crank case of the engine.

What I claim is:—

1. An internal combustion engine, comprising a crank case, a cylinder mounted on the case and having ports in its side, a piston both reciprocable and rotative in the cylinder and having a port to communicate with said cylinder ports and with the interior of the cylinder, a crank shaft in the case connected to the piston, an annular rotating member within the crank case, means for actuating said member from the crank shaft, and means, extending within the cylinder and carried around near the wall of the same by said rotating member, said means having slidable engagement with the piston, 70 to rotate the same.

2. An internal combustion engine, comprising a crank case, a cylinder mounted on the case and having ports in its side, a piston both reciprocable and rotative in the cylinder and having a port to communicate with said ports and with the interior of the cylinder, a crank shaft in the case connected to the piston, gearing inclosed within the crank case and operated by the shaft and a member extending within the cylinder and carried around near the wall of the same by the gearing and also slidably engaging the piston to rotate the same. 85

3. An internal combustion engine, comprising a cylinder having an exhaust port and an inlet port in its side and spaced apart, a piston having a vertical passage open at the top and side, and communicating with said ports, a crank shaft below said cylinder, a rod connected to the piston at one end and to the crank shaft at the other end, an annular gear surrounding the connecting rod and spaced apart therefrom, half time gearing connecting the said gear and the crank shaft and a rod carried by the said gear slidably engaging the piston to rotate the same. 90

4. An internal combustion engine, comprising a cylinder having ports in its side, a piston both reciprocable and rotative in said cylinder and having a lateral opening to communicate with said ports and a vertical passage open at the top and communicating with said opening near the bottom, means for operating said piston, a vertically disposed rod slidable in the side of the piston, a gear carrying the rod around at a distance from the axis of the cylinder and means for rotating said gear operated by the engine. 100

5. An internal combustion engine, comprising a case, a crank shaft journaled in the case, a cylinder mounted on the case and having an inlet port and an exhaust port in its side spaced apart, a piston both reciprocable and rotative in the cylinder, a rod connecting the piston and crank shaft, an annular miter gear surrounding the connecting rod and spaced apart therefrom, a timer shaft journaled in the case, half time gears 115 120 125 130

connecting said shaft and the crank shaft, a miter gear mounted on said timer shaft and engaging the annular gear to rotate the same and a rod carried by the annular gear and slidably engaging the piston to rotate the same one revolution to each cycle of the engine.

In testimony whereof I affix my signature in presence of two witnesses.

LOUIS FRANCIS CLARK.
